TEMPERATURE CONTROL MEANS FOR
WASHING MACHINES AND THE LIKEHerbert Harvey, Los Angeles, Calif., assignor to
Leo M. Harvey, La Canada, Calif.

Application August 14, 1940, Serial No. 352,583

3 Claims. (Cl. 236—46)

This invention relates to controls and relates more particularly to temperature controls for washing machines and the like. A general object of this invention is to provide an effective, dependable, temperature control for commercial washing machines and other devices carrying on stage or cyclic operations.

In clothes washing machines, intended for use in commercial laundries and adapted to carry on cyclic washing operations, it is important to maintain given temperatures in the washing compartments or shells during the various operations. I will herein make reference to the invention employed in connection with a clothes washing machine of the class for performing cyclic washing operations to govern the temperature in the washing chamber or shell, it being understood that the invention is not to be construed as limited or restricted to this particular use application.

Another object of this invention is to provide a temperature controlling mechanism operable by a time control or timing device to govern the operation of a valve for discharging steam or other heating medium, or to govern other heating means for the washing compartment of a clothes washing machine carrying on cyclic washing operations, to provide and maintain given temperatures in the compartment at given or selected phases of the washing operations.

Another object of this invention is to provide a control means of the character referred to that is operable to produce and maintain different temperatures in the washing compartment during the different stages or cycles of the washing operation and for stages or operation cycles of varying duration.

Another object of this invention is to provide a temperature control means that may be controlled or operated by a timing mechanism of the washing machine to produce and maintain any selected temperature for any given duration, and at any time, as determined by the settings and actions of the timing mechanism.

Another object of this invention is to provide a temperature control of the character referred to that is entirely automatic and that requires no manual adjustment, regulation or attention.

Another object of this invention is to provide a temperature control of the character referred to that includes a thermostatic means responsive to the temperatures in the washing compartment or shell to govern a valve control or the like, which thermostatic means is auto-

matically set for given temperatures and for operation at given time intervals by a novel means which is responsive to a timer for timing the various operations of the washing machine.

5 Another object of this invention is to provide a timing mechanism that is adapted to remote control and operation as by electrical circuits, and that is adapted to be arranged at any point where its thermostat means is affected by the 10 temperatures in the washing compartment or shell.

A further object of this invention is to provide a temperature control for a washing machine that is safe and dependable and that 15 cannot cause the discharge of the heating medium or steam at the wrong time.

The various objects and features of my invention will be fully understood from the following detailed description of typical preferred 20 forms and applications of the invention, throughout which description reference is made to the accompanying drawings, in which:

Fig. 1 is a schematic view of a portion of a washing machine illustrating the manner in 25 which the control of the present invention is associated therewith. Fig. 2 is an enlarged vertical detailed sectional view taken as indicated by line 2—2 on Fig. 1 illustrating the principal parts of the control. Fig. 3 is a vertical detailed 30 sectional view taken as indicated by line 3—3 on Fig. 2. Fig. 4 is an enlarged fragmentary horizontal detailed sectional view taken as indicated by line 4—4 on Fig. 3. Fig. 5 is an enlarged view of the steam valve and its operating 35 means with the valve broken away in part to appear in vertical cross section. Fig. 6 is a perspective schematic view of the control illustrating the electrical circuits, Fig. 7 is a fragmentary sectional view of another form of temperature responsive means that may be embodied in the invention and Fig. 8 is a diagrammatic view of still another form of the invention.

40 In the drawings I have shown the improved control of the invention associated with a washing machine having a stationary shell 10 and a rotatable or oscillatable cylinder 11 in the shell. The shell 10 has an inlet 12 through which the water, washing mixtures, etc., are introduced, 45 and has a dump valve 13 by which it may be emptied. A pipe 14 carrying steam or other heating medium such as hot water discharges into the lower part of the shell 10. The cylinder 11 is perforated as is customary in machines 50 of this class and serves to contain the clothes 55

to be washed. The heating medium or steam supplied by the pipe 14 heats the water and washing mixtures contained in the washing compartment or shell 10.

A valve 15 is connected in the pipe 14 to control the delivery of the heating medium or steam to the shell 10. The valve 15 is provided with the usual closure 16 for controlling the flow through a port 17 in the partition of the valve. A stem 18 projects upwardly or outwardly from the valve closure 16. The washing machine is equipped with a timing mechanism 19 for initiating and stopping the various stage washing operations through the medium of suitable electrical circuits. The timer 19 includes a drum 20 rotated by a synchronous motor (not shown), or the like, to turn at a given speed. The drum 20 is formed of cardboard, paper, or the like, so that slots, notches, or grooves may be formed in its periphery for the control and operation of various governing elements, as will be later described. The timer 19 is described and claimed in a copending application, Serial No. 352,584, filed August 14, 1940, Patent No. 2,306,056, December 22, 1942, and the drum 20 forms the subject of a co-pending application, Serial No. 382,834, filed March 11, 1941, Patent No. 2,333,248, November 2, 1943.

The control of the present invention may be said to comprise, generally, an electrical operating means 21 for the valve 15, a housing or case 22, regulable thermostat means 23 carried by the case 22 to be responsive to temperatures in the shell 10 and operable to control the valve operating means 21, power driven means 24 in the case 22 for regulating or setting the thermostat means 23, means 25 operable by the timer 19 for controlling the means 24, and a safety means 26 for rendering the valve operating means 21 inoperative at the end of each cycle of operation.

The means 21 for operating the valve 15 is under the control of the thermostat means 23 and the safety means 26. The means 21 includes a solenoid 27 associated with the valve 15. As illustrated in the drawings, the solenoid 27 may be mounted on the body of the valve 15 to have its armature or movable element 28 connected with the stem 18 of the valve closure 16. With the solenoid 27 deenergized the closure 16 closes the port 17 to prevent the flow of steam or heating medium to the shell 10. The operating circuit for the solenoid 27 may comprise a line or lead 29 extending directly to a power line 30 and a lead 31 in which the switches of the means 23 and 26 are interposed. Fig. 6 of the drawings best illustrates the operating circuit for the means 21. The lead 31 extends from the solenoid 27 into the case 22 and then passes from the case to the second power line 32.

The housing or case 22 carries the thermostat means 23, the regulating or operating means 24, the safety means 26 and other elements. The case 22 may be suitably positioned on the washing machine, for example, it may be arranged adjacent the shell 10. The housing or case 22 includes a front section 33 and a rear section 34. The sections 33 and 34 are complementary opposing dished or cup-shaped members. The rear edge of the section 33 has a groove 35 carrying a ring of sealing or packing material 36. The forward edge portion of the rear section 34 is received in the groove 35 to engage the ring 36. Studs 37 are threaded in thickened parts of the rear section 34 and extend outwardly to project through openings in the front section 33.

Nuts 38 are threaded on the projecting parts of the studs and clamp against the front section 33 to hold the case assembled. An observation window 39 provided with a transparent pane of glass, or the like, is provided in the forward wall of the front section 33. The rear side of the section 34 has a pocket 40 closed by a removable cover plate 41.

The regulable thermostat means 23 is operated or regulated by the means 24 under the control of the means 23 and is responsive to the temperature in the washing shell 10. The means 23 is operated by the means 24 to be responsive to any given temperature and serves to control the valve operating means 21 to maintain said temperature in the shell 10. The thermostat means 23 may be varied considerably in type and detail without departing from the invention. In Figs. 1 to 6, inclusive, of the drawings I have shown a thermostat means 23 of the general class described in Patent No. 1,975,856, which embodies a switch 42. The means 23 as illustrated, includes a tube or hollow stem 43 extending into the shell 10, or a fitting on the shell, and provided at its outer end with a tip 44 which houses a bimetallic means responsive to the temperature in the shell. The conventional bimetallic means illustrated comprises a spiral bimetal member 9 having one end fixed to a turnable shaft 48. An adjusting sleeve 53 carries a stop 8 engageable by the other end of the member 9 whereby the tendency of the member to change in shape when subjected to temperature changes may cause turning of the shaft 48. The stem 43 is suitably supported in an opening 45 in the back wall of the case section 34 and a calibrated dial 46 is fixed on its inner end within the case 22. The case 42a of the switch 42 is secured to the dial 46 by spaced pins or studs 47 and is spaced forwardly from the dial. The shaft 48 extends forwardly from the tube 43 and projects into the case 42a of the switch 42 to control the switch. The switch 42 of the thermostat means 23 is preferably a mercury tube switch and is connected with the thermostat shaft 48 to be operated thereby. The shaft 48 is turnable by the temperature responsive bimetallic means of the thermostat to open and close the switch 42. The switch 42 is interposed in the lead 31 of the valve operating means 21, and assuming that the circuit for the means 21 is otherwise complete, the switch 42 is operable to control the valve 15 through the medium of the solenoid 27.

The thermostat means 23 further includes a regulating or setting mechanism comprising an arm 49 movable across the dial 46. The arm 49 is notched at its outer end and has a pointer 50 in its notch 51 which cooperates with the calibrations 52 on the dial 46. The regulating arm 49 is fixed to the bushing or sleeve 53 which surrounds the thermostat shaft 48 and extends into the tube 43. The sleeve 53 is operatively connected with the regulating means of the thermostat. Turning of the arm 49 or movement of the arm across the dial 46 sets or regulates the temperature responsive means of the thermostat so that the shaft 48 turns to cause opening and closing of the switch 42 at any given temperature, as indicated by the finger 50 at the dial 46. The thermostat means 23 including its switch 42 and its regulating means is well known to those skilled in the art and its details do not form parts of the present invention except as they may be used in combination with the elements of the invention.

The means 24 is operable to move the regulating arm 49 of the thermostat means 23 and thus govern operation of the thermostat means. The means 24 includes a power unit in the form of an electric motor 54. The motor 54 is arranged in the case 22 to have its shaft 55 above and in parallel relation to the shaft 48 of the thermostat means 23. As illustrated, the motor 54 may be supported on the rear case section 34 by legs 56 secured to lugs 56 on the case section. The motor 54 is preferably, though not necessarily, a synchronous motor. In the simple case illustrated the motor 54 is shown connected with the power lines 30 and 32, it being understood that where a synchronous motor is employed the required energizing and exciting leads are installed. A capacitor 57 for the motor circuit is suitably mounted in the case 22. The motor shaft 54a passes rearwardly through an opening in the wall of the case section 34 to project into the pocket 40. A pinion 58 is fixed to the motor shaft 54a. A horizontal shaft 59 is rotatably supported in an opening 60 in the wall of the housing section 34 and is spaced below the motor shaft 54a. A gear 61, considerably larger in diameter than the pinion 58, is fixed to the projecting rear portion of the shaft 59 to mesh with the pinion 58. The pinion and gear drive 58-61 provides for a substantial speed reduction between the shafts 54a and 59. A flange 62 is provided on the forward end of the shaft 59 to engage against the thickened part of the section 34 around the opening 60. An eccentric is provided on the forward end of the shaft 59. In the construction illustrated a separately formed eccentric 63 has a stem 64 threaded in an opening in the shaft 59 to project from the forward end of the shaft. A head 65 is provided on the forward end of the eccentric 63.

The means 24 further includes a ratchet drive between the gear shaft 59 and the regulating arm 49 of the thermostat means 23. A tubular boss 66 is provided on the rear section 34 of the case 22 and carries an anti-friction bearing 67, see Fig. 3. A ratchet disc or segment 68 is supported by the bearing 67 for free turning or oscillation. Rings 69 are riveted or otherwise secured to the segment 68 and fit about the bearing 67 to retain the segment thereon. The segment 68 projects upwardly beyond the regulating arm 49. A clip 70 is secured to the segment 68 and has a finger 71 engaging in the notch 51 of the arm 49 to operatively connect the segment 68 with the regulating arm. Ratchet teeth 72 are provided on the upper edge of the segment 68. A ratchet pawl 73 is supported on the above described eccentric 63 of the shaft 59. The ratchet pawl 73 extends horizontally above the segment 68 and has a laterally projecting finger 74. The lower edge of the finger 74 is bevelled to cooperate with the teeth 72 of the segment 68. The pawl 73 is spring-held or spring-urged so that its finger 74 properly cooperates with the ratchet teeth 72. A depending arm 75 is provided on the pawl 73 and a spring 76 has one end anchored in the case 22 and its other end secured to the arm 75 to urge the pawl 73 into cooperation with the ratchet segment 68. It will be seen that each rotation of the eccentric 63 produces a reciprocatory motion of the ratchet pawl 73 and the bevelled edge of the pawl finger 74 cooperating with the teeth 72 advances the segment 68 with each reciprocation of the pawl. The segment 68 is moved or advanced a given distance with each rotation of the eccentric 63.

and in practice this distance may substantially equal the width of a ratchet tooth 72.

A releasable holding pawl 77 is provided to hold the segment 68 in its adjusted or advanced positions. A pin 78 projects from the rear wall of the case section 34 and pivotally supports the pawl 77 above the ratchet disc 78 so that it opposes the advancing pawl 73. A laterally projecting finger 79 is provided on the forward side of the pawl 77 and has a bevelled lower edge for cooperating with the teeth 72 of the segment 68. The rear or outer end of the holding pawl 77 has a depending arm 80 and a spring 81 is secured to the arm 80 and is anchored in the case 22 to yieldingly hold the pawl 77 in its active position.

The means 25 is operable by the timer or timing mechanism 19 to initiate and terminate operation of the motor 54 and thus determine when the thermostat means 23 is adjusted for operation and the temperature to which the thermostat means is adjusted. The means 25 is also operable by the timer 19 to release the means 24 and cause restoration of the thermostat means 23. The timer actuated means 25 includes a switch 83 connected in a lead 82 of the motor 54, see Fig. 6. This switch 83 is a spring-held switch that is normally urged closed by its spring means and the switch is bodily carried by a block or arm 84. The arm 84 is in turn supported by a rod or shaft 85 to pivot or turn. The shaft 85 extends parallel with the shaft of the timer drum 20 and the switch 83 is governed by the drum 20. A leaf spring finger 86 is attached to the arm 84 and carries a roller 87 which cooperates with or rides on the rotating drum 22. The spring finger 86 is engageable with the operating stem 88 of the switch 83. The parts are related so that the cooperation of the roller 87 with the normal periphery of the drum 20 holds the spring finger 86 flexed where it cooperates with the switch stem 88 to hold the switch 83 open.

When the roller 87 enters a slot or groove 89 in the drum 20 the spring finger 86 flexes free of the switch stem 88 or flexes to a position to allow the switch 83 to close. When the roller 87 moves out of the groove 89, due to rotation of the drum 20, the spring finger 86 is flexed to act on the stem 88 and open the switch 83. Accordingly, the switch 83 is closed during the period the roller 87 is in the slot or groove 89 and the location and length of the groove determine when the thermostat means 23 is operated and the temperature to which it is adjusted. The drum 20 may have one or more slots or grooves 89 in the path of the roller 87 and the grooves may be cut to adapt the machine to provide any selected temperatures in the shell 10 at any selected times for the desired cyclic washing operations. The drum 20 is formed of a material that is readily provided with the slots or grooves 89 and the drum is replaceable so that the machine may be made to provide heating periods at any selected times and of any selected temperatures for different cyclic washing operations, by merely replacing the drum 20 with other drums having grooves 89 located and proportioned to produce the desired results.

A spring 90 acts on the lower portion of the switch arm 84 to maintain the roller 87 in correct cooperation with the drum 20. This spring 90 may be arranged under compression between the arm 84 and a fixed part at the timer 19. Manual means is preferably provided for operating the switch 83. This manual means may com-

prise a push button 91 on the arm 84 accessible at the exterior of the timer case. When the operator pushes the button 91 the arm 84 is pivoted against the action of the spring 90 to move the switch stem 88 away from the roller spring finger 86 so that the switch 83 may close. Thus the operator may cause operation of the motor 64 and resultant regulation of the thermostat means 23 at any time and for any period. The dial 46 and the finger 80 may be seen through the window 39 so that the regulation of the thermostat means 23 by the automatic action of the means 25 or by manual depression of the button 91 may be checked at any time.

The means 25 further includes a mechanism for restoring or resetting the thermostat means 23 at the end of each heating operation. A tension spring 92 has one end secured to the segment 68 and its other end anchored in the case 22. The spring 92 is under tension and tends to move the segment 68 back to its original position and thus tends to restore the thermostat means 23 to its low initial setting. The ratchet pawl 77 of course operates to prevent the return of the segment 68 when the means 24 is active.

Electromagnetic means is provided for releasing both ratchet pawls 78 and 77 at the end of the heating operations to allow the return of the thermostat means 23 by the spring 92. A slide block or releasing member 93 is arranged in the case 22 at the rear of the pawls 78 and 77. A pin 94 on the rear section 34 of the case 22 extends through a vertical slot 95 in the member 93 and has an enlargement or head at the forward side of the member. The pin 94 guides the member 93 for vertical shifting. A laterally projecting arm 96 is provided on the lower end of the member 93 and is arranged so that its upper edge may engage against fingers 97 and 98 projecting rearwardly from the pawls 78 and 77 respectively. An electromagnetic coil or solenoid 99 is provided to operate the member 93. The solenoid 99 is supported in the upper portion of the case 22 and a stem 100 on its armature or movable member has a yoke receiving the upper portion of the member 93. A pin 101 connects the yoke part of the stem 100 with the member 93. When the solenoid 99 is deenergized the member 93 is in its lower position where its finger 96 is clear of the pawl fingers 97 and 98. When the solenoid 99 is energized the member 93 is shifted upwardly and its finger 96 acts on the pawl fingers 97 and 98 to pivot the pawls 78 and 77 upwardly. This frees the pawl fingers 74 and 78 from the teeth 72 of the segment 68 and the spring 92 swings the segment 68 back to its initial position to restore or reset the thermostat means 23. A stop 102 is formed on the interior of the case 22 and is engageable by the segment 68 to limit the return movement of the segment. The stop 102 may be located to prevent the return of the thermostat means 23 to its zero position.

The pawl releasing solenoid 99 of the means 25 is under the control of the timing mechanism 19. One lead 103 of the solenoid 99 extends to the power line 30 while the other lead 104 of the solenoid extends to the timing mechanism 99 and then passes to the other power line 32. A switch 83^a is interposed in the solenoid lead 104 and is under the control of the drum 20 of the timing mechanism 19. The switch 83^a may be identical with the switch 83 and is controlled and operated in the same manner as the switch 83. The switch 83^a is carried by an arm 84^a pivoted on shaft 85 and is operated by a leaf spring

finger 86^a carrying a roller 87^a which rides on the drum 20. The roller 87^a engaging the normal periphery of the drum 20 holds the switch 83^a open. One or more slots or grooves 105 are cut in the drum 20 in the path of the roller 87^a. When the roller 87^a enters a groove 105 the switch 83^a closes to energize the solenoid 99. The slots or grooves 105 may be located to cause energization of the solenoid 99 and the resultant restoration of the thermostat means 23 at any selected times. Restoration of the thermostat means 23 in this manner may be accompanied by termination of the heating cycle and the positions of the slots or grooves 105 on the drum 20 thus determine the temperature at which the heating cycles are stopped. The switch 83^a may be manually controlled by a push button 91^a on the block 84^a and the block 84^a is spring-urged by a spring 90^a. The various elements associated with and controlling the switch 83^a may be the same as the corresponding elements associated with and controlling the switch 83. The slots or grooves 105 are readily cut in the drum 20 to provide for termination of the heating periods or cycles at the selected times, and the drum 20 may be replaced by drums having grooves 105 located to terminate the heating operations at different times. The energization of the solenoid 99 need only be instantaneous or for short durations and the slots or grooves 105 may be quite short.

The means 26 is a safety means operating to positively prevent opening of the valve 15 after the thermostat means 23 has been restored to its normal position at the end of the heating cycles. The means 26 controls the energizing circuit 29-31 of the valve operating means 21 and includes a switch 106 interposed in this circuit. In practice the switch 106 is connected in series with the switch 42 of the means 23. The switch 106 may be spring held and is normally urged closed. A suitably insulated mounting block 107 is secured in the case 22 to support the switch 106 in a position adjacent the dial 46. A stem 108 is provided on the switch 106 and projects from the mounting block 107. A leaf spring arm 109 is provided on the block 107 and is arranged to engage and operate the switch stem 108. A bracket or yoke 110 is secured to the outer end of the spring arm 109 and carries a rotatable roller 111. The roller 111 is arranged to engage or rest on the periphery of the thermostat dial 46 when the arm 109 is clear of the switch stem 108. A part associated with the thermostat shaft 48 or the ratchet segment 68 operates the switch 106. In practice the regulating arm 48 of the thermostat means 23 may serve as the operating element for the switch 106. When the thermostat means 23 is in its normal position with the segment 68 engaged on the stop 102 the regulating arm 48 engages the roller 111 to hold the switch 106 open. When the segment 68 is moved by the power driven regulating means 24 the arm 48 moves out of engagement with the roller 111 and the spring arm 109 flexes to permit closing of the switch 106. When the arm 48 moves out of engagement with the roller 111 the roller engages against the dial 46. It will be seen that the switch 106 is always open when the thermostat means 23 is in its normal condition with the segment 68 engaging on the stop 102 and is closed only when the thermostat means is adjusted by the power driven means 24. Accordingly, the valve 15 cannot be opened except during the timed periods when the thermostat means 23 is

adjusted and under the control of the means 24 and 28.

A terminal block 112 of insulating material may be secured in the case 22 and the various electrical leads 31, 82, 103, 104, etc., entering the case 22 through a conduit 114 may be connected with posts 118 of the block. The block 112 is of course suitably insulated or formed of insulating material.

It is believed that the operation of the timed temperature control of the invention will be understood from the foregoing detailed description. In the cyclic operation of the washing machine hot and cold water and the various aqueous washing solutions, bleaching solutions, etc. are discharged into the shell 10 through the inlet 12 at successive periods and are successively discharged through the dump valve 13. The materials being washed are contained in the cylinder 11 to be acted on by the various washing solutions. During certain of the washing operations it is desirable to maintain given temperatures in the shell 10. The drum 20 of the timing mechanism 19 may be provided with slots or grooves 89 and 105 to control the means of the invention so that it produces and maintains the desired temperatures in the shell 10 at the desired periods of the washing operation. It has been described above how the grooves or slots 89 and 105 may be provided in the drum 20 to operate the switches 83 and 83^a at selected times. When the rollers 87 and 87^a are engaged on the normal periphery of the drum 20 the solenoid 27 is de-energized and the valve 15 is in the closed condition.

When rotation of the drum 20 brings a groove 89 into position to receive the roller 87 the switch 83 is closed and the circuit to the motor 54 is completed. Operation of the motor 54 is accompanied by rotation of the eccentric 63, the eccentric being driven at a relatively slow rate because of the speed reduction gearing 58-61. The rotating eccentric reciprocates the pawl 73 and the pawl cooperating with the teeth 72 advances the segment 68. Movement of the segment 68 from its normal position against the stop 102 releases the arm 49 from the roller 111 and the switch 106 closes. The extent of advancement or movement of the segment 68 depends upon the length of the groove 89 and, therefore, the setting or adjustment of the thermostat means 23 is determined by the length of the groove. When the groove 89 passes the roller 87 the switch 83 opens and the motor 54 is de-energized. The holding ratchet 77 serves to hold the segment 68 and the thermostat means 23 in the adjusted or advanced condition. The operation thus far described adjusts or conditions the thermostat means 23 to respond to a temperature in the shell 10 determined by the length of the groove 89.

In the event that the temperature in the shell 10 is below that determined by the automatic setting of the means 23 as above described, the thermostat means closes the switch 42 to complete the circuit to the solenoid 27 and the valve 15 is opened. Opening of the valve 15 results in the discharge of steam or other heating medium into the shell 10 to increase the temperature in the shell. When the correct temperature has been reached in the shell 10 the thermostat means 23 reopens the switch 42 to de-energize the solenoid 27 and the valve 15 closes. In some cases the valve 15 may be opened and closed as just described several times during a given washing operation or cycle.

The heat providing and maintaining cycle con-

tinues until a slot or groove 105 of the drum 20 reaches the roller 87^a. When this occurs the roller 87^a drops into the groove 105 and the switch 83^a closes to energize the solenoid 99. Energization of the solenoid 99 causes simultaneous release of the two pawls 73 and 77 and the spring 92 restores the segment 68 and the thermostat means 23. During the restoring movement the regulating arm 49 engages the roller 111 to open the switch 106. The segment 68 is stopped by the stop 102 is a position where the arm 49 holds the switch 106 open. Opening of the switch 106 prevents subsequent energization of the valve opening solenoid 27 by the action of the thermostat means 23, so that the temperature condition in the shell 10 no longer affects the operation of the valve 15. The cycle of operation of the temperature control means is completed with the opening of the switch 106 and the mechanism remains idle until a slot or groove 89 moves to a position to receive the roller 87 which results in the starting of another cycle of operation.

Fig. 7 illustrates a form of the invention embodying a remotely regulable or controllable heat responsive means. In this construction the thermostat or heat responsive means comprises an expansible diaphragm 120 of selected form, a fluid bulb 121 to be exposed to the temperature conditions of the washing shell 10 and a capillary tube 122 extending between and connecting the diaphragm and bulb. The communicating diaphragm 120 and bulb 121 carry or contain a suitable temperature responsive vapor or fluid. The bulb 121 may be arranged to be exposed to the fluid in the washing shell. The capillary tube 122 may be of any reasonable length and the diaphragm 120 may be positioned as desired at a point remote from the bulb 121. Accordingly, the diaphragm 120, and the parts associated therewith, may be located at a convenient, accessible and visible position at the front, exposed side of the machine or elsewhere. A stem or plunger 123 is fixed to a side of the expansible diaphragm 120 to operate a switch 124. In the drawings the switch 124 is illustrated diagrammatically, it being understood that I prefer to employ a snap switch or toggle switch. The switch 124 is connected in the circuit 29-31 in the same manner as the switch 42 and has the same function as the switch 42.

The diaphragm 120 and the switch 124 are related for relative movement and either of these elements may be moved with respect to the other, as desired. In the case illustrated it will be assumed that the switch 124 is stationary and that the expansible diaphragm 120 is movable with respect to the switch. Means is provided for moving or adjusting the diaphragm 120 to regulate the temperature responsive means. A boss 125 may be fixed to the diaphragm 120 and may be provided with a polygonal stem 126 slidably received in an opening in a stationary plate 127. A screw 128 extends from the stem 126 to protrude through a boss 129 on the plate 127. The stem 126 and the screw 128 are rigid with a side of the diaphragm 120. An actuating nut 130 has threaded engagement with the screw 128 and bears against the boss 129. A collar 131 is fixed to the boss 129 and has flanged engagement with the nut 130 to hold the same against endwise movement. A hand or dial 132 is fixed to the nut 130 and has an indicating finger 133. The dial 132 may be calibrated or may cooperate with calibrations on the plate 127 or other stationary object. The finger 133 of the above described clip

78 cooperates with the finger 133. With this arrangement turning of the ratchet sector 88 by the means 24 results in turning of the nut 130 and produces longitudinal movement of the screw 128. It will be seen that the means 24 is operable to move the diaphragm 120 toward and away from the switch 124. Movement of the diaphragm 120 away from the switch 124 regulates the thermostat means so that a higher temperature must be reached in the shell 10 to produce closing of the switch 124. With movement of the diaphragm 120 toward the switch 124 the thermostat means operates at a lower temperature to close the switch 124. It is believed that it will be understood how the means 24 governs the temperature responsive means. The other elements of the apparatus of Fig. 7 may be as above described and may have the same operation.

Having described only typical preferred forms and applications of my invention, I do not wish to be limited or restricted to the specific details herein set forth, but wish to reserve to myself any variations or modifications that may appear to those skilled in the art or fall within the scope of the following claims.

Having described my invention, I claim:

1. A temperature control for a washing machine having a washing container with a heating medium supply pipe and having an operation timer, the control comprising a valve in said pipe, means for opening the valve including an energizing circuit, regulable thermostat means responsive to temperatures in the container and including a switch in said circuit, the thermostat means having a normal setting where the switch is open and being regulable to close the switch in response to different temperatures in the container, regulating means operable to regulate the thermostat means, means governed by the timer for operating the regulating means at predetermined times and for predetermined periods to cause regulation of the thermostat means to given settings, means tending to restore the thermostat means to its normal setting, releasable means for holding the thermostat means in its regulated settings, means governed by the timer for releasing the releasable means at given times to terminate the periods during which the thermostat means is operable to close the switch in response to selected temperatures in the container, a part on the thermostat means movable therewith during setting and restoration of the same, and a second switch in said circuit which is opened by said part to render the valve opening means ineffective when the thermostat means is returned to its normal setting.

2. In combination with a washing machine having a fluid containing washing compartment, a pipe for supplying a heating medium to the compartment and a valve controlling said pipe,

5 a control for maintaining selected temperatures in the compartment at given stages of the washing operation comprising means for opening the valve, an operating circuit for said means, regulable means responsive to temperatures in the compartment and including a switch in said circuit, the regulable means being adapted to be regulated to close the switch in response to selected temperatures in the compartment and including a turnable regulating member, a motor having an energizing circuit, a drive between the motor and the regulating member whereby the motor is operable to turn the member from a normal position to advanced positions, a switch 10 in the motor circuit, a timer normally holding the last named switch open and operable to cause closing of said last named switch at a given time and for a given interval, whereby the temperature responsive means is regulated to respond to a selected temperature, means for restoring the member to its normal position, a second switch 15 in said operating circuit, a part turnable with said member cooperating with said second switch to hold said operating circuit open when the member is in its normal position, releasable means for holding the member in its advanced positions, electromagnetic means for releasing said releasable means and having a control circuit, and a normally open switch in the control 20 circuit closed by the timer at a given time to terminate the period during which the temperature responsive means is responsive to said selected temperature.

3. A temperature control mechanism for regulating the temperature of a liquid in a container 35 comprising a heating medium supply means for supplying heating medium to the container, a valve for controlling said supply means, means for opening said valve including an energizing circuit, a thermostat responsive to temperature 40 in said container and including a switch in said circuit, the thermostat being biased to a normal position where the switch is open and being regulable to close the switch in response to different temperatures in the container, turnable regulating means for regulating the thermostat, a timer, means governed by the timer for operating the regulating means at predetermined times and for predetermined periods to cause regulation of the thermostat to given settings, releasable means for 45 holding the thermostat in its regulated settings, means governed by the timer for releasing the releasable means to terminate the periods during which the thermostat is operable to close the switch, a second switch in said circuit and an element movable with the regulating means operable to open said second switch when the thermostat returns to its normal setting to de-energize 50 said circuit.

HERBERT HARVEY.
